(57) **CLAIM**

The ornamental design for a light source, as shown and described.

DESCRIPTION

FIG. 1 is a front perspective view of a light source showing my new design;

FIG. 2 is a front view of the light source;

FIG. 3 is a back view of the light source;

FIG. 4 is a right side view of the light source;

FIG. 5 is a left side view of the light source;

FIG. 6 is a top view of the light source;

FIG. 7 is a bottom view of the light source; and,

FIG. 8 is another front perspective view of the light source including optical fiber and needles in communication therewith.

The broken line showing of the optical fiber and needles in FIG. 8 illustrates the environment of the claimed design and form no part thereof. All other broken lines illustrate portions of the Light Source and form no part of the claimed design.
